United States Patent Office.

JOHN S. PERRY, OF ALBANY, NEW YORK.

Letters Patent No. 94,026, dated August 24, 1869.

IMPROVEMENT IN PORTABLE HEATING-ATTACHMENT FOR STOVES.

The Schedule referred to in these Letters Patent and making part of the same.

To all whom it may concern:

Be it known that I, JOHN S. PERRY, of Albany, in the county of Albany, and State of New York, have invented a new and improved Portable Heating-Attachment for Stoves; and I do hereby declare that the following is a full, clear, and exact description thereof, reference being had to the accompanying drawings, making part of this specification, in which—

Figure 1, sheet 1, is a perspective view, showing one form of my improved heater applied to a cooking-stove.

Figure 2, sheet 1, is a longitudinal section, taken vertically through the centre of the heater.

Figure 3, sheet 1, is a section, taken transversely through the centre of the heater.

Figure 4, sheet 2, is a sectional view of an improved heater, differing somewhat from that shown in figs. 1, 2, and 3.

Similar letters of reference indicate corresponding parts in the several figures.

The nature of my invention consists—

First, in a portable warming-chest, containing a fixed or removable water-reservoir, and adapted for being applied to or detached from the escape-pipe of a stove, for cooking or heating-purposes, so as to receive the heated products of combustion on their way from such stove to the main flue or chimney, and thereby utilize a large percentage of the heat for warming water or other purposes, as will be hereinafter explained.

Secondly, in a portable heating-chest, containing a water-reservoir, in combination with a pendulous escape-pipe, or a pipe which is carried below the top of said chest, either through the said reservoir, or on one side thereof, whereby the heated products received from the flues of a stove will be caused to accumulate about the walls of the reservoir, and communicate a large amount of heat to the water therein, as will be hereinafter explained.

Thirdly, in a portable chest, which is provided with inlet and outlet-pipes, a water-reservoir, and a warming-closet, so arranged, that when applied to a stove, the heated products leaving the flues of the stove shall circulate around the walls of the reservoir and closet before escaping from the chest, as will be hereinafter explained.

I am aware that portable radiators and "drums" of various descriptions have been used in conjunction with the escape-flues or pipes of stoves, for receiving the products of combustion on their way to a chimney, and thus radiating a large amount of heat into apartments. I am furthermore aware that it is not new to construct cooking-stoves with permanent extended flue-chambers, constituting parts of the bodies of the stoves, for receiving or containing water-reservoirs, and allowing the heated products of combustion to circulate about the walls of the reservoirs before escaping into

the main flues. I am also aware that portable warming-closets, for keeping dishes and other things warm, have been appended to the back walls of cooking-stoves, so as to receive heat radiated through these walls. But I am not aware that a portable apparatus or heater, adapted for being applied to any size or form of stove, communicating with the flues thereof, and constructed substantially as hereinafter described, has ever been known or used prior to my invention thereof.

To enable others skilled in the art to understand my invention, I will describe the best means known to me for carrying it into effect.

In the accompanying drawings—

A represents a chest, which may be made of any suitable capacity or shape, and which may be composed, wholly or in part, of sheet or cast-metal, properly mounted and strengthened.

B is the base of this chest, which may be so applied as to be removable, for cleaning the interior of the chest, and removing, from time to time, accumulations of soot and ashes which will collect therein.

C is a pipe or orifice through one side of the chest, which is adapted to receive the collar around the escape-flue of a stove, or to receive a pipe leading from such escape-flue, in order to establish communication between a stove and the interior of a chest.

D is a water-reservoir, which is sustained, by its top flange, upon the top plate of the chest A, so that its bottom and side walls will be exposed to the action of the heated products of combustion caused to circulate within the chest, and so that a chamber, P, will be formed around the reservoir, for containing and retaining a large amount of heat.

This water-reservoir D, which may be permanently fixed to chest A, or detachable therefrom, has openings through its top, provided with hinged covers b b; and it is also constructed with a flue, C², passing up centrally through its interior, and out through a top plate between the doors or covers b b, as shown in figs. 1, 2, and 3.

This flue or pipe is adapted for receiving, in its lower end, a pipe, C¹, which, if used, extends down nearly to the bottom of chest A, on one side of the centre thereof, and serves to conduct the spent products of combustion, through pipe C², to the main flue or chimney, after the products circulate through the interior of the chest.

The pipe C² communicates with the ascending flue C¹, near its upper end, and lies in a horizontal position, directly in line with the inlet-orifice C, as shown in fig. 3.

This pipe or flue C² is provided with a damper, g, which can be regulated by a rod, g', extending outside of the case A, as shown in fig. 2.

Below pipe C², and extending horizontally through

the chest A, is a closet or chamber, G, closed, at one or both ends, by doors a, and surrounded by a chamber, c.

When the chest A is put in communication with the escape-flue of a stove, and fire made in the latter, the escaping products will enter this chest through the orifice C, and rise therein, and fill the dead-air space P, surrounding the water-reservoir. As the chest becomes warmed, the products will descend, around the warming-closet G, to the base B, thence rise through pipes C¹ C², and escape into the chimney.

If a direct draught is required at any time, the damper g is opened, which will cause most of the products to pass directly from orifice C, through pipe C², into the ascending pipes C¹ C².

The pipes C¹ C² may be dispensed with, and the products carried off through the pipe C², as shown in fig. 4, sheet 2; and, if desirable, this pipe C² may be arranged outside of the water-reservoir, although, when carried through it, a large amount of heat will be communicated to the water in this reservoir, which would otherwise be carried off into the chimney.

It will be seen, from the above description, that as the natural tendency of the heated products on entering chest A is to rise to the top of this chest, and accumulate in the space P, surrounding the water-reservoir, and as this tendency will only be counteracted in part by the ascending draught through flue C², there will be a large amount of heat conducted into space P, and absorbed by the water in the reservoir D; and as the products of combustion gradually lose their heat in this space, they will descend, and give place to a further supply of heat.

While I prefer to utilize the space beneath the water-reservoir D, for containing a warming-closet, I do not confine myself to the use of such closet; and while I prefer to arrange the water-reservoir wholly within the chest A, so that its side and bottom walls shall not be impinged upon by cold air, I do not confine myself to such arrangement, as a part of the reservoir may be exposed above the top of the chest.

My improved portable warming-chest and reservoir combined is adapted for being fitted closely to the back of a flat-back stove, as shown in fig. 4, sheet 2, so that a large amount of heat will be radiated into the chest

through this back wall. If constructed for such a stove, one of the side walls of the chest might be omitted, so as not to obstruct radiation of heat from the said wall; and at any time when it is not desired to use the improved heater, it can be readily removed, and the escape-pipe leading to the chimney connected directly to the collar surrounding the escape-orifice of the stove.

For a cooking-stove having an "extension-top," (by my invention such extensions on stoves may be dispensed with,) the chest A may be made to communicate with the flue of such stove by a short pipe.

I am not restricted to size or shape in the construction of my portable heaters, for they do not constitute a part of the body of the stove to which they may be applied; and they may be applied to stoves, ranges, furnaces, or heating-apparatus of various descriptions, which materially differ from them in size and shape.

I do not claim as my invention such a heating-attachment as is shown in the schedule annexed to the Letters Patent of George W. Gillet, dated December 29, 1868.

Having described my invention,

What I claim as new, and desire to secure by Letters Patent, is—

1. A portable warming-attachment for stoves, consisting of a chest, A, a reservoir, D, and inlet and outlet-passages, adapted to operate substantially as described.

2. A portable warming-attachment for stoves, combining the following elements, to wit, a chest, A, an outlet-flue, C²; a warming-closet, G, and an inlet-orifice, C, substantially as described.

3. The direct flue C², provided with a damper, g, and arranged, in the relation described, to the inlet-orifice C, for the purpose described.

4. The descending flue C¹ C², passing through the reservoir D, and extending down nearly to the bottom of the portable chest A, within which such reservoir is arranged, substantially as and for the purpose described.

JOHN S. PERRY.
